FIG. 6.

FIG. 7.

Inventor:
FRANK MARQUART
By

Frease, Merkel and Saywell
Attorneys.

UNITED STATES PATENT OFFICE.

FRANK MARQUART, OF CLEVELAND, OHIO.

SAFETY DEVICE FOR POWER WRINGERS.

Application filed April 20, 1921. Serial No. 463,068.

To all whom it may concern:

Be it known that I, FRANK MARQUART, a citizen of the United States, resident of Cleveland, county of Cuyahoga, and State of Ohio, have invented new and useful Improvements in Safety Devices for Power Wringers, of which the following is a specification, the principle of the invention being herein explained and the best mode in which 5 I have contemplated applying that principle, so as to distinguish it from other inventions.

My invention relates to safety devices for wringers, used in washing clothes, and particularly to devices of this character for use upon power wringers. More particularly, my invention relates to a safety device positioned adjacent the wringer and adapted to control an electric switch in series with the 10 circuit by means of which the wringer and usually the associated tub are operated. My improvements are not limited to use with wringers but are capable of general application to many kinds of power machines 15 which are provided with moving exposed dangerous elements and are operated or fed by workmen adjacently positioned.

The annexed drawings and the following description present in detail one form of my 20 invention, the same disclosing, however, but one of the many forms in which the spirit of my invention may be exemplified.

In said annexed drawings:

Figure 1 represents a front elevation of a 25 wringer in connection with the operations of which my improved safety device is utilized;

Figure 2 represents a horizontal section, taken in the plane indicated by the line 30 II-II, Figure 1, and illustrating particularly a plate which is moved transversely of the wringer as the safety device is operated;

Figure 3 represents a longitudinal vertical 35 section of a portion of an electric switch utilized in connection with the operation of my improved safety device;

Figure 4 represents a vertical transverse section, taken in the plane indicated by the line IV-IV, Figure 3;

Figure 5 represents a vertical transverse section, taken in the plane indicated by the line V-V, Figure 3;

Figures 6 and 7 represent plan views of a wringer in connection with which my improved safety device is utilized, showing, respectively, operating and open positions of the device;

Figure 8 represents an end elevation of the wringer and safety device, the cover of the switch box being removed and the switch 55 being in closed position; and

Figure 9 represents a view similar to that shown in Figure 8, except that the safety device and the switch are shown in open position.

Referring to the annexed drawings in which the same ordinals in the several views refer to like elements, a wringer is suggested by the ordinal 1, having the operating rolls 2 and 3. The wringer, as is true of standard 60 apparatus of this character, is presumed to be operated by gearing or other suitable power-transmitting means from a motor which usually also operates an associated tub. Whenever the hands, hair or clothing 65 of the operator are drawn in by the rolls of the wringer or become entangled in the other moving elements thereof, or the clothes which are being wrung become wrapped about the rolls or otherwise entangled in the mechanisms, it is desirable and necessary, of course, quickly to stop the wringer. My invention relates to this 70 wringer-stopping class of safety devices, inasmuch as I do not attempt to free continuously-operating rolls one from the other or practice any one of the other expedients 75 variously utilized for minimizing the dangers incident to any one of the contingencies hereinbefore mentioned. Now, in order to 80 stop the wringer, it is necessary to open the circuit passing the power both for the tub and the wringer. The switch is usually positioned upon the tub and almost invariably 85 is positioned a considerable distance from the wringer so that it is not available for quick operation, particularly if some part of the operator's person or some of her clothing are caught in the wringer.

An essential element of my invention is 90 the provision of an electric switch adjacent the wringer and preferably supported upon the wringer frame. To this end I locate the switch 5 for the motor (not shown) adja-

2
cent to and preferably upon the wringer frame 1, the conductor being indicated by the ordinal 4. I provide upon the two sides of the wringer members 6 and 7 which are 5 preferably thin frame members presenting broad bearing surfaces, as plainly shown in Figure 1, and extending across the respective faces of the wringer 1, said members 6 and 7 being hinged to one end of the 10 wringer frame at one end 8 and resiliently spaced at the other end 9 from the other end of the wringer frame. The ends 9 of the bearing members 6 and 7 are, however, secured together by means of a transverse 15 member 10, preferably a metal plate, of the form and design shown in Figure 2, the detail of which will be hereinafter fully explained. It is evident, therefore, that a swinging movement of either of the members 20 6 or 7 upon the end 8 will cause the other member to move contrariwise relatively to the wringer 1, an equal distance. The members 6 and 7 are normally spaced equal distances from the wringer 1 at the ends 9, 25 by means of coil springs 11 and 12, Figure 8, disposed between the frame of the switch 5 and the inner faces, respectively, of the bearing members 6 and 7.

The transverse metal connecting member 30 10 is formed with two end slots 13 and 14, through which screws 15 and 16 pass for the purpose of holding and aligning said member upon the switch frame 1 and yet permit a limited transverse movement in 35 either direction. Furthermore, said connecting member 10 is formed with an elongated central slot 17 having enlarged areas 18 and 19 at its respective ends. The normal width of the slot 17 permits the passage 40 therethrough of a pin 20 but does not permit the passage therethrough of an enlarged portion 21 of said pin 20. The diameter of the areas 18 and 19, however, is great enough to permit the passage 45 therethrough of said enlarged portion 21 of the pin 20. Secured to the top of the pin 20 is an operating button 22. The pin 20 is further formed with a shoulder 23 adjacent- 50 ly below the enlarged portion 21 which has a diameter greater than that of the areas 18 and 19, so that the upward movement of the pin 20 is limited by the stop formed by said shoulder 23. The central portion of the pin 20 consists of an elongated thin flat 55 portion 24, whose form is plainly shown in Figures 3 and 5. At its bottom end said pin 20 is formed into another cylindrical portion 25, similar to the upper enlarged portion 21.

60 Secured to a wringer frame member 1' is a coil spring 26, also secured at its other end to the bottom face of the bottom cylindrical portion 25 of the pin 20. The tension of the spring 26 is such that it tends to lift the 65 pin 20 so that the enlarged portion 21 thereof

will rise above the transverse plate 10, i. e., the position shown in Figure 9. This last-mentioned position is that in which the switch controlling the wringer operation is in its open position. The detail of the 70 switch is no part of my invention and I shall explain enough of this detail and have shown enough in the accompanying drawings to illustrate how the vertical actuation of the pin 20 will open and close the switch. 75 It is sufficient to say, in so far as my invention is concerned, that the control of the movements of the pin 20, as effected by my invention, results in the opening and closing of the switch so as to effect the proper 80 functioning of my safety device.

Referring now to certain details of the standard switch which I have shown for purpose of illustration, it will be noted that a swinging double contact member is 85 indicated by the ordinal 27, having the end leaf contacts 27' adapted to close or open the circuit by being in registry or out of registry with the contacts 27². This contact member 27 is rigidly secured upon one face 90 of a cam member 28 which is rotatably secured to a pin 29. Secured to one edge of the plate portion 24 of the pin 20, is an angular arm 30 and the opposite edge of said plate 24 is formed with a laterally ex- 95 tended longitudinal projection 31, forming at its ends upper and lower shoulders 32. The plate 24 is formed with an elongated slot 24' intermediate the arm 30 and the extension 31. Mounted upon the switch 100 housing is an irregularly shaped member consisting of a flat substantially rectangular portion 34, disposed upon one side of the plate 24 and an arcuate member 35 disposed upon the opposite side of the plate 24. This member 35 is formed with an arcuate slot 35'. Within this slot the angular member 36 of the cam member 28 is adapted to play. The plate portion 24 of the pin 20 moves vertically relatively to the pin 29 105 through the medium of the elongated slot 24', said plate 24 being guided by means of the members 34 and 35 over which it slides and a confining shoulder 33 formed 110 upon the pin 29. The rectangular member 34 is formed with a pair of oppositely disposed lugs 37 adapted to pass through slots (not shown) formed in the arms 38' of a three sided spring member 38 secured at 115 the point 38², to the outer edge of the member 34. A coiled spring 39 is mounted upon the pin 29 and, in either of the closed or open conditions of the switch, bears with its tensioned ends upon the arm 36 of the cam member 28 secured to the pin 29 and to 120 which the reciprocating contact member 27 is secured. The ends of the spring 39 are indicated, respectively, by the ordinals 40 and 41, Figure 3, this figure showing the 125 open condition of the switch.

It will be evident from the foregoing description and the accompanying drawings that, the switch being closed, as shown in Figure 8, if, for any reason, pressure is put upon either of the bearing members 6 and 7, the same will be moved inwardly at the end 9 toward the rolls 2 and 3 of the wringer, the other pressure member being moved outwardly an equal distance; that this inward movement, for instance, a movement of the member 6, Figures 7 and 9, will be against the tension of the spring 11, resulting also in an elongation of the spring 12, that just so soon as this movement results in bringing enlarged portion 21 of the vertical pin 20 into alignment with the enlarged area 18 of the slot 17, the spring 26 will force said pin 20 upwardly until the shoulder 23 abuts the vertically rigid metal connecting member 20; that said upward movement of the pin 20 will cause the upper shoulder 32 formed by the lateral extension 31 to move the upper arm 38' of the spring member 38; that during this upward movement of the member 20, the annular arm 30 projecting from the plate portion 24 will lift the end 40 of the spring 39, thus causing said spring to tend to turn the cam member 28 and hence the contact member 27, this movement of the cam member 28, under the pressure of the end 40 of the spring 39 being prevented by reason of the fact that end shoulders 38' of the spring arms 38' abut shoulders 28' of the cam member 28, preventing the latter from turning; that just so soon as the upper shoulder 32 of the extension 31 formed upon the plate member 24 lifts the upper spring arm 38' and consequently lifts the upper holding member 38' above the shoulder 28', the cam 28 will be free to swing, under the tension of the end 40 of the spring 39, so that said spring end 40 will move the arm 36 of the cam member 28 in the arcuate slot 35 and to the upper part of said slot, as shown in Figure 5, resulting in the turning movement of the cam 28 and, consequently, of the contact member 27 to its open position. The result is, that the several elements are disposed in the positions shown in Figure 9, the electric switch being open. It is evident that, because there can be no relative transverse movement between the enlarged portion 21 of the pin 20, and the slot 17, the compressed spring 11 cannot push the bearing member 6 out to its normal position, nor can the extended spring 12 pull the bearing member 7 into its normal position. However, when the operating button 22 is manually depressed, the enlarged portion 21 of the member 20 is pushed below the slot 17, and the members 6 and 7, under the action of the springs 11 and 12, assume their normal positions. Furthermore, the downward actuation of the member 20 results in co-operative movements of the spring elements

contrariwise to those just described in detail, effecting the closing of the switch. This downward movement of the member 20 also subjects the spring 26 to compression, said compressed spring, however, being rendered ineffective because the transverse movement of the members 6 and 7 into their normal positions has resulted in bringing the narrow portion of the slot 17 adjacently above the enlarged portion 21 of the member 20 so that said member 20 cannot be moved upwardly by the compressed spring 26.

I wish particularly to point out that any movement, voluntary or involuntary, of the operator's body toward the wringer 1, will necessarily result in an inward movement of either the bearing member 6 or member 7, effecting by the means shown and described, an opening of the switch. It is evident that any dangerous movement of the operator's body, due to the entanglement of any portion of the body or of the clothing in the rolls or other wringer elements would be inwardly of the wringer and that, therefore, any such dangerous entanglement will result in stopping the wringer. Of course, the switch can be instantly opened by means of the operator voluntarily pushing a bearing member 6 or 7 to its inner position, but in the absence of such voluntary action, the involuntary movement of the operator's body would result necessarily in a pressure being put upon the bearing member 6 or 7 to open the switch, before such movement of the operator's body or clothing into the wringer rolls had assumed dangerous proportions.

What I claim is:

1. In safety devices for power wringers, the combination with a wringer and a source of power including a switch; of a pair of pressure members hinged at one end upon the opposite faces, respectively, of said wringer and adjacent one end of the latter, said members extending across the faces of the wringer; coiled springs spacing the other ends, respectively, of said members from the other end of said wringer; means normally holding the switch closed; means tending to open the switch; and means actuated by the inward movement of either of said pressure members and adapted to permit said opening means to function.

2. In safety devices for power wringers, the combination with a wringer and a source of power including a switch; of a pair of pressure members hinged at one end upon the opposite faces, respectively, of said wringer and adjacent one end of the latter, said members extending across the faces of the wringer; coiled springs spacing the other ends, respectively, of said members from the other end of said wringer; a transversely extending member secured to said pressure members adjacent their free ends; means co-operating with said transverse member to

hold the switch closed; and means tending to open the switch, the inward movement of either of said pressure members neutralizing the cooperation of said transverse member and said means to permit said opening means to function.

3. In safety devices for power wringers, the combination with a wringer and a source of power including a switch; of a pair of pressure members hinged at one end upon the opposite faces, respectively, of said wringer and adjacent one end of the latter, said members extending across the faces of the wringer; coiled springs spacing the other ends, respectively, of said members from the other end of said wringer; a transversely extending member secured to said pressure members adjacent their free ends; means co-operating with said transverse member to hold the switch closed; means tending to open the switch, the inward movement of either of said pressure members neutralizing the cooperation of said transverse member and said means to permit said opening means to function; means holding said pressure members, respectively, in the inner and outer positions assumed by the inward actuation of one of the pressure members; and means for manually closing said switch, the actuation of said manual means permitting the pressure members to assume their normal positions.

4. In safety devices for power wringers, the combination with a wringer and a source of power including a switch; of a pair of pressure members hinged at one end upon the opposite faces, respectively, of said wringer and adjacent one end of the latter, said members extending across the faces of the wringer; coiled springs spacing the other ends, respectively, of said members from the other end of said wringer; a transversely extending member secured to said pressure members adjacent their free ends; said transverse member being formed with an elongated slot having a pair of enlarged spaced areas; a vertically disposed pin transversely intersecting said slot and formed with a shoulder of a diameter greater than said slot and less than the enlarged areas thereof; means limiting the vertical movement of said pin; an operating button secured to one end of said pin; and a coiled spring tending to move said pin through said slot, said pin being connected to the switch.

5. In safety devices for power wringers, the combination with a wringer and a source of power including a switch; of a member supported by the wringer frame and movable toward and from the wringer; means co-operating with said member and connected to said switch automatically to open the latter upon the inward movement of either of said member; means holding said member in

its inner position; and manually-operable means for closing said switch, said holding means being rendered ineffective by the closing of the switch, permitting said member to assume its normal position.

6. In safety devices for power wringers, the combination with a wringer and a source of power including a switch; of a member hinged at one end to the wringer frame; a coiled spring spacing the other end of said member from said frame; means co-operating with said member and connected to said switch automatically to open the latter upon the inward movement of said member; means holding said member in its inner position; and manually-operable means for closing said switch, said holding means being rendered ineffective by the closing of the switch, permitting said spring to move said member to its normal position.

7. In safety devices for power wringers, the combination with a wringer and a source of power including a switch; of a pair of members supported by the wringer frame and respectively movable toward and from the two sides of the wringer; means co-operating with said members and connected to said switch automatically to open the latter upon the inward movement of either said members; means holding said members in their inner positions; and manually-operable means for closing said switch, said holding means being rendered ineffective by the closing of the switch, permitting the members to assume their normal positions.

8. In safety devices, the combination with a machine having movable dangerous elements and provided with a switch; of a movable pressure member supported by the machine frame adjacent said elements; means cooperating with said member and connected to said switch automatically to open the latter upon the movement of said member, said means holding said member in its moved position; and manually-operable means for closing said switch, said holding means being rendered ineffective by the closing of the switch, permitting said member to assume its normal position.

9. In safety devices, the combination with a machine having movable dangerous elements and provided with a switch; of a pair of pressure members supported by the machine frame adjacent said elements and respectively movable upon end pivots toward and from the latter; means cooperating with said members and connected to said switch automatically to open the latter upon the inward movement of either of said members; manually-operable means for closing the switch; and means controlled by the switch-closing means and tending to move said members respectively to their normal positions.

10. In safety devices, the combination

with a machine having movable dangerous elements and provided with a switch; of a pair of pivotally-connected pressure members supported by the machine frame adjacent opposite sides of said elements; means cooperating with said members and connected to said switch automatically to open the latter upon the movement of said members; manually-operable means for closing the switch; and means controlled by the switch-closing means and tending to move said members to their normal position.

Signed by me this 4th day of April, 1921.

FRANK MARQUART.
